RING DISPLAY HOLDER

Abraham G. Sager, 910 W. Jackson Blvd., Chicago, Ill.

Filed Mar. 28, 1960, Ser. No. 59,920

Term of patent 14 years

(Cl. D80—9)

The figure is a top perspective view taken from one side and one end of a ring display holder embodying my new design, the bottom and the opposite end walls being substantially plain and the opposite side being essentially the same as the side shown.

I claim:

The ornamental design for a ring display holder, as shown, and described.
